SELECTIVELY OPERABLE MECHANISM

Mahlon W. Kenney, River Forest, Ill.

Application July 3, 1936, Serial No. 88,812

7 Claims. (Cl. 74—10)

My invention relates in general to adjusting apparatus and has more particular reference to the adjustment of radio receivers.

An important object is to provide improved means for adjusting apparatus to any selected one of a number of adjusted positions; a further object being to provide means manually operable to tune a radio receiver to condition the same to a desired broadcasting station, the invention employing bracing apparatus for shifting the tuning means of the receiving apparatus, including automatically operating means for stopping the adjusting means in adjusted position.

Another important object is to provide adjusting means in the form of a rotatable dial adapted to be twirled manually, including means manually operable as a part of the twirling action to stop the adjusting means in a selected adjusted position; a further object being to provide means to stop the adjusting apparatus in a desired position regardless of the direction of dial twirling movement.

Another important object is to provide means operable during the twirling movement of the dial to render inactive the apparatus being adjusted so that, where applied in a radio receiver, unpleasant and undesirable blurry sounds caused by adjusting the receiver, when in active condition, rapidly through a number of station receiving positions, may be eliminated by rendering the receiver inactive during the adjusting operation.

Another important object is to provide adjustable tuning means for radio receivers, including means operable automatically during the tuning period to quiet the receiver, whereby the station, to which the receiver is tuned before commencing the adjustment, is silenced and the receiver remains inactive, emitting no sound whatever, until the tuning operation is completed at which instant the receiver becomes active in the new adjusted position.

Another important object is to provide adjusting means for the tuning condensers of an electrical apparatus such as a radio receiver, including an improved yielding drive free from backlash, interconnecting the adjustable condensers with the condenser adjusting mechanism, in order to prevent the condenser from receiving mechanical strains as a result of undue operation of the adjusting means.

Another important object is to provide selective adjusting apparatus, including a preferably annular selector dial adapted to be manually actuated to accomplish the adjustment, said manually adjustable selector dial having means, pref-

erably in the form of openings for the reception of the finger of an operator, to permit facile twirling of the adjusting means, and means forming stops having portions extending in said opening and operable, upon insertion of a finger in its corresponding opening, to stop the movement of the adjusting apparatus in adjusted position corresponding with the opening in which the finger is inserted to accomplish the adjustment, so that to accomplish a desired adjustment it is merely necessary to insert a finger in the opening of the selector dial corresponding to the desired adjusted position and twirl the dial to such position at which the apparatus will be automatically stopped.

Another important object is to form the stop means as a button, the head of which extends in the finger opening of the selector dial and is adapted to receive indicia corresponding with the adjusted position controlled by said button; a further object being to mount the button on a stem sliding in the turnable portions of the adjusting apparatus and normally urged, as by a spring, into position in which the stop means controlled by the button is inoperative, said stem carrying means shiftable, upon depression of the button, into position to stop the adjusting means in a desired tuned position upon twirling the selector dial.

Another important object is to provide stop mechanism adapted to cooperate with the depressable button when the same is in depressed position to stop the adjusting mechanism in the desired angular position regardless of the direction in which the button controlled stop approaches tuned position so that the mechanism may be stopped exactly in the desired adjusted position whether the selector dial is turned in clockwise or counter-clockwise direction.

Another important object is to provide means for stopping the adjusting mechanism in tuned position comprising a tilting bracket having a portion affording stop means adapted to cooperate with the button stop when the same is depressed in the selector plate, the bracket being movable to permit its stop portion to shift a predetermined distance in either direction, the displacement of said stop portion in either direction being limited so that the depressed button stop, and hence the turnable adjusting means on which it is mounted, may be stopped in the same adjusted position regardless of the direction in which it approaches the stop portion of the tilting bracket.

Another important object is to provide unitary,

rigid frame means, preferably in the form of a die casting, upon which the movable portions of the adjusting apparatus, including the twirlable selector dial, the depressable selector button and 5 the tilting stop bracket, are mounted, the adjustment indicating means being also mounted on the die casting.

Another important object is to provide, in combination with the automatic adjustment selector 10 mechanism, manually operable means preferably in the form of a turnable knob operable to adjust said mechanism to any desired adjusted position including positions intermediate those permitted by the selector buttons; a further object being to 15 provide double ratio auxiliary adjusting means of the character mentioned providing for either rapid or relatively slow adjustment of the mechanism; and a still further object is to drivingly connect the auxiliary manually operable adjusting means with the automatically selective apparatus whereby adjustment by the auxiliary means is accomplished at least in part through the mechanism of the automatic selector mechanism, the driving connection between the auxiliary 20 adjusting means and the automatic selector mechanism being preferably accomplished by belting the auxiliary means upon a drumlike portion of the selector mechanism.

Another important object is to form the turnable portions of the automatic selector mechanism as a rotatable assembly, including a spaced apart 30 pair of indexing rings upon which the depressable selector buttons are carried; a further object being to arrange said indexing plates with a series 35 of equally spaced openings for slidably receiving the button shafts whereby they are all supported in parallel spaced relationship by both of the indexing plates, the foregoing arrangement providing an extremely simple and inexpensive manner 40 of supporting the selector buttons since both of the indexing plates contain corresponding perforations and may be formed in a common die.

Another object is to provide each of the selector buttons with a stop in the form of a stem 45 mounted on the button stem in position parallel therewith and adapted to be assembled for sliding movement in one of a plurality of indexing perforation sets formed in the indexing plates whereby the stop means of each button may be 50 accurately angulated on the index plate means to occupy the exact position required to stop the adjusting mechanism exactly in the desired adjusted position.

Another important object is to form the indexing plates with corresponding sets of perforations, each set comprising a central perforation and additional perforations arranged concentrically about the central perforation, the concentrically arranged perforations being disposed so that 55 the radial lines through the axis of the index plate and through each of said perforations are separated by a predetermined angle, whereby the stop shaft of a selector button may be accurately angulated on the index plate by inserting it in 60 one of the circularly arranged openings, when the stem of the button is assembled in the central opening of the set.

Another important object is to allow for indexing the stop mechanism by providing index 70 plate means having a guide opening for each stop button assembly and a plurality of openings arranged circularly about the guide opening and in any one of which circular openings the stop portion may be inserted to index the same to a 75 required stopping position on the index plate.

Another important object is to form the selector button with exposed means for carrying indicia to identify the buttons, the buttons being formed to permit orientation of the indicia carrying means in the button after the stop assembly 5 with which the button is associated has been indexed.

Another object is to form the indicia carrying means as discs arranged in a card in position to be punched therefrom ready for assembly on the 10 push buttons, the discs forming the card being printed with standard indicia for the purpose of identifying adjusted positions controlled by the stop buttons.

Another important object is to provide means 15 to facilitate the indexing of the stop buttons by providing a target visible through the openings of the index plates so that the turnable adjusting mechanism may be set to the desired adjusted position and the push button stop assembly indexed on the indexing means by assembling the same in the openings of the indexing means which are in alignment with said target; a further object being to form the target as a pin displayed in front of a contrasting background to render 25 the pin highly visible; a still further object being to form the background as a strip of sheet metal colored white, the target pin being colored black and preferably comprising the stop element carried in the tilting stop frame previously mentioned, the background strip also being preferably carried in said tilting frame in position to be illuminated by lamps forming a part of the indicator.

Another important object is to provide, in a 30 radio receiver having an A. F. C. circuit and automatic station-selecting means, means operable to render the A. F. C. circuit inactive as the receiver reaches tuned position, in order that a 35 precision adjustment may be had; a further object being to accomplish the foregoing by providing a grounding switch for the A. F. C. circuit, which switch is normally open but is operatively associated with the tuning mechanism, more particularly the tilting stop frame thereof, 40 whereby the A. F. C. circuit is grounded when the button controlled stop element shifts the tiltable stop frame upon reaching adjusted position; and a further object is to form the grounding switch as a resilient element normally urging 45 said tilting stop frame to assume a neutral position in which said grounding switch is open.

Another important object is to provide an adjusting device more particularly for the tuning 50 condensers of a radio receiver, which tuning device is directly connected with the tuning condenser and is arranged for rotary movement within a tuning range embracing at least one hundred eighty degrees.

Another important object is to provide an improved illuminated indicator having general utility but particularly well adapted for use in radio receivers having the automatic station selector means heretofore mentioned, said indicator including relatively shiftable dial and pointer means, the dial preferably adapted for stationary mounting within the twirlable selector dial which, incidentally, may form a frame for a window covering the dial, the dial being of translucent material, such as glass, and being supported in front of a screen having openings through which light from a source back of the screen may be directed upon the translucent dial element to illuminate the same by refraction; a further object being to form the screen with a plurality of 70 75 80 85 90 95

openings, each in position opposite a scale of the dial, a separate light source being provided for each opening so that by selectively operating the light sources, one of the several scales 5 may be indicated as operative; and a further object is to provide means for directing the light from each source only through its corresponding opening in the screen and to prevent light from one source from penetrating 10 the screen opening corresponding with another source.

Another important object is to employ stationary lamps as illuminated scale indicating means and to differentiate the several scales of the indicator by selectively operating the lamps.

Another important object is to provide an illuminated indicator dial comprising a preferably glass plate, an apertured screen behind the plate and means to illuminate the indicator by 20 means of light striking the glass plate through the screen openings and without employing light sources to illuminate the edge of the glass plate.

Another important object is to provide a preferably Celluloid sheet carrying means forming 25 scales printed on the sheet, said sheet being mounted in front of the glass plate whereby said sheet and plate comprise an indirectly illuminated scale dial, the scale indicia on the sheet being displayed against a background of suffused 30 illumination provided by the glass plate.

Another important object is to form scale identifying indicia on the dial in position opposite the openings of the backing screen so that the names of the several scales may be silhouetted in said 35 openings when the lamps are energized therewith.

Another important object is to provide a radio receiver including a loud speaker or sound reproducer enclosed in a cabinet, the lateral walls 40 of which are curved to minimize cabinet reverberation and permit sound reproduction to be accomplished in highly accurate fashion.

These and numerous other objects, advantages and inherent functions of the invention will 45 become apparent as the same is more fully understood from the following description which, taken in connection with the accompanying drawings, discloses a preferred form of the invention.

50 Referring to the drawings:

Figure 1 is a front elevation view of a radio receiver provided with the selective adjusting mechanism embodying my present invention;

Figure 2 is a sectional view taken substantially 55 along the line 2—2 in Figure 1;

Figure 3 is a sectional view taken substantially along the line 3—3 in Figure 2;

Figure 4 is a sectional view taken substantially 60 along the line 4—4 in Figure 2;

Figure 5 is a partial and fragmentary front view of apparatus embodying my present invention;

Figures 6 and 7 are sectional views taken substantially 65 along the lines 6—6 and 7—7, respectively, in Figure 4;

Figure 8 is an exploded perspective view of parts forming the apparatus of my present invention; and

Figure 9 is a sectional view taken substantially 70 along the line 9—9 in Figure 8.

To illustrate the invention, I have shown on the drawings a radio receiver 11 having adjustable means 13, namely, condensers whereby the radio receiver may be tuned to adjust the same 75 for the reception of signals within the operating

range of the receiver, although it will be apparent that the device of my present invention is not necessarily restricted to the adjustment of radio receivers. The present invention, however, relates to means operable automatically to turn the 5 adjustable means 13 to any one of a number of predetermined adjusted positions and to this end I provide adjusting means 15, drivingly connected with the adjustable means 13, the adjusting means being supported on a preferably unitary, 10 rigid frame 17, forming a support on which all of the mechanism hereinafter described is mounted. The frame 17 is provided with a mounting lug 19, by means of which it may be attached on a mounting 21, which is secured in any suitable 15 fashion as on the frame or casing of the receiver 11. The lug 19 also affords means for attaching a support bracket 23 on which the adjustable means 13 is mounted in substantially fixed relationship with respect to the frame 17. The ad- 20 justable means 13 also may have a shaft 25 projecting therefrom toward the frame 17 and the frame is or may be formed with spaced journal portions 27 forming mountings for a shaft 29, the axis of which is preferably substantially in 25 line with the axis of the shaft 25.

The frame 17 may be formed conveniently as a die casting and provides portions 31 on which may be mounted, indicating means for showing the adjusted position of the device 13, said in- 30 dicating means preferably comprising a stationary graduated dial 35 carried in a frame 37 which in turn is mounted on a bracket 39, the bracket 39 being secured on the mounting portions 31 of the support frame 17 by means of fastening 35 screws 41, or other suitable securing means. The indicator also preferably comprises pointers 43 and 45, the pointer 43 being mounted on a shaft 47, which is directly connected to and turns with the shaft 29, whereby the pointer 43 directly in- 40 dicates the adjusted position of the condenser means 13. The pointer 43 preferably has indicating portions 51 and 53 extending oppositely from the shaft 47 in position to sweep in front of the dial 35. The pointer 45, however, is carried on a 45 sleeve 49 which embraces the shaft 47. The sleeve 49 is preferably connected through suitable gearing 55 with the shaft 29, the gear ratio preferably providing a 12 to 1 ratio so that the pointer 45 may travel completely around the dial 50 while the pointer 43 is traveling $\frac{1}{2}$ of the dial.

The shaft 29 carries a support spider 57 splined thereon between the bearing portions 27, said spider comprising a hub 59 embracing the shaft 29 and a segmental portion, embodying strength- 55ening ribs 61 extending radially of the hub 59, having a marginal edge 63 subtending an angle of approximately 135 degrees with respect to the axis of the shaft 29.

It will be seen that the segmental spider may 60 rotate through substantially 180 degrees, rotation thereof in either direction being limited by engagement of the opposite edges of the segment on the frame 17. I prefer also to provide embossments 64 on opposite sides of the frame 17 in 65 position to engage preferably resilient buffers 66, which are set in the edges of the segmental spider 57. In this manner the rotation of the spider may be limited so that when drivingly connected with an adjustable device such as the 70 condenser of a radio receiver, the movement of the spider in either direction may be limited whereby to prevent the condenser from being shifted beyond a predetermined limit, thus preventing damage to the condenser by eliminating 75

- the possibility of over-travel of the spider, and the other elements of the adjusting apparatus, all of which form a relatively heavy assembly which might damage the condenser were it not 5 for the protective stops afforded by the means 64 and 66. The support spider 57 has a socketed portion 65 in which is mounted a pin 67 which extends toward the adjustable device 13, the pin 67 affording means to drivingly connect the 10 spider with the condenser shaft 45 for the purpose of turning the same in accomplishing adjustment of the means 13. To this end the shaft 25 carries resilient crank means 69 comprising a hub 71 and an arm 73 extending radially in position to engage one side of the pin 67, said arm 73 having a springlike clip 75 engaging the opposite side of the pin 67, whereby said pin is resiliently secured in driving relationship with respect to the crank means 69.
- 20 By turning the spider 57 on the axis of its supporting shaft 29, the shaft 25 of the adjustable means 13 may be turned to any desired adjusted position. An important object of my present invention is, however, to provide manually operable 25 means adapted, upon turning the adjusting mechanism, to cause the same to stop automatically at a position selected by the operator of the adjusting device, and to this end I provide convenient means 77 manually operable to turn the 30 spider 57 and hence the adjustable device 13, including selective means 79 operable as an incident to the turning of the means 77 to cause the frame 57, and hence the adjustable device 13, to stop in the preselected adjusted position.
- 35 The device 77 preferably comprises an escutcheon plate formed of sheet metal or other suitable material, and comprising a preferably annular ring having a plurality of spaced apart openings 81, behind which the selector means 79 are arranged in position for operation upon insertion 40 of a finger in a selected one of the openings 81. The escutcheon plate forms a mounting for a window element 83 and is supported on the frame 57 in position such that the escutcheon plate overlies an opening 85 formed in a wall 87 of the 45 cabinet in which the adjustable receiver mechanism 11 is mounted, the window element 83 being supported in front of the indicator dial 35 so that said dial is displayed centrally of or within the escutcheon plate.
- 50 The selector means 79 is mounted on the spider 57 behind the escutcheon plate and turns with said plate and spider. The selector means preferably comprises selectively operable stops supported in index plate means comprising an index 55 plate means of preferably annular configuration, including a pair of spaced apart index plates 89 and 91, said plates being held in spaced apart relationship by means of spacer sleeves 93 and secured upon the circular segmental rim 63 of the spider, by means of studs 95, which penetrate openings in the plates, extend through the sleeves 93 and preferably thread into embossments 97, formed on the rim of the spider 65 57. The index plates are thus supported in spaced relationship relatively rigidly with respect to the spider, the plates encircling the indicator supporting portions 31 of the frame 17. The escutcheon plate is supported on and from 70 the indexing means by spacing elements 99 which interconnect the escutcheon plate with the indexing plate 91, so that the escutcheon plate and the indexing plates are supported in substantially parallel relationship, and it will be 75 seen that the escutcheon plate, the indexing

plates and the spider form a rotatable assembly on the shaft 29. The stop means 79 is carried on and by the indexing plates, and comprises a plurality of depressible stems 101, slidably mounted and guided by the indexing plate means 5 opposite the openings 81 of the escutcheon plate, there being a depressible element 101 opposite each of the openings 81. The stems 101 are guided in openings in the plate 91 and extend toward the openings 81. Each stem carries a 10 push button 103 opposite its corresponding opening 81. The resilient means, preferably a coiled spring 105 encircling each stem 101, are provided to normally urge the stems toward the escutcheon plate. The stem in each carry a link 15 107 affording a mounting for a stop pin 109, which pin is fixed on and extends parallel with respect to its corresponding pin 101, and extends through openings in the indexing plates 89 and 91. The pins 109 extend rearwardly of the indexing means, but are held normally in restricted position. By pressing upon any one of the several push buttons 103, however, the push button assembly may be depressed on the indexing means against the urge of the spring 105 and 20 the stop pin 109 projected rearwardly of the plate 89 into position, as shown in dotted lines in Figure 4, to engage a stop pin 111, which is mounted on the stationary frame 17. It will be seen, therefore, that by inserting a finger in one 25 of the openings 81 the escutcheon plate and also the indexing plates, as well as the spider 57, may be easily rotated in either direction. The assembly rotated in this fashion includes the stop means 79. Insertion of a finger in an opening 30 81, in order to thus turn the rotatable assembly incidentally causes depression of the button 103 at the opening 81 and projects the stop pin 109 into position such that when the rotating assembly has moved through a distance corresponding to the selected opening 81, the pin 109 35 will engage the stop element 111, whereupon further turning of the rotatable assembly will be stopped. By properly positioning the pin 109, it will be seen that stoppage of the assembly 40 may be accomplished in a position in which the spider 57, through its driving pin 67, will have turned the shaft of the means 13 to an exact and predetermined adjusted position.

I desire, however, to insure that stoppage of 45 the mechanism is accomplished at the same relative position regardless of the direction in which the pin 109 approaches the stop pin 111. If the stop pin 111 is rigid on the frame 17, it 50 will be seen that the shiftable device will not be stopped in the same position, but the stopping position, when the device is turned in one direction, will be displaced from the position of stoppage in the other direction by a distance equal to the sum of the diameters of the pins 109 55 and 111. I therefore support the pin 111 with its axis in the plane in which I desire to stop the axis of the pin 109 when adjusted position is reached, and to this end I mount the pin 111 in a bracket or frame 113, preferably comprising a 60 bent sheet metal strip having an upper arm 115 and a lower arm 117, the stop element 111 comprising a cylindrical stem fixed at its opposite ends to the terminal portions of the arms 115 and 117. The frame 113 is tiltably mounted on 65 a shaft 121, which in turn is secured as by threading in a socket 123 formed in the bracket 17. The arms 115 and 117 have cut-out openings 125 including a notched portion 127 defined by spaced fingers 129 between which the stop ele- 70 75

ment 111 is assembled, the ears 129 being bent inwardly upon and around the element 111 to hold the same in place in the bracket 113. I provide means for limiting the tilting movement 5 of the bracket 113 about the pin 121 in order that when the stop pin 109 engages the element 111 in one direction, said element may shift sufficiently to permit the stem 109 to occupy a position in which its axis lies exactly in the 10 desired adjusted position, the bracket permitting the element 111 to shift in the opposite direction when engaged by the pin 109 to permit said pin to occupy the same adjusted position when approaching from the other direction. To 15 this end the bracket 115 is formed with a cut-out portion 131 adapted to receive a projection 133 which is formed preferably as an integral part of the frame 11. The opposed edges of the cut-out 20 131 are adapted to engage the opposite sides of the projection 133 and thus limit the tilting movement of the frame 113 in either direction about its support pin 121 to accomplish the stopping movement, heretofore described, to the end that the pin 109 may be stopped with its axis 25 in the same position regardless of the direction from which the pin 109 approaches the stop element 111.

The escutcheon plates 89 and 91 are formed with a plurality of openings for the reception of the pins 101 and the stop pins 109. These openings are arranged in sets as shown in Figure 5, each set including a central opening 135 for the reception of the pin 101 and a plurality of openings 137 arranged concentrically around the central opening 135 in order that the pin 109 of each button may be assembled in any one of the openings 137 in order to enable the pin 109 to be indexed as closely as possible to the exact position enabling it to accomplish tuning automatically by stopping the rotary tuning movement of the spider and hence of the shaft 25 on the exact position to which the shaft is necessarily turned in accomplishing the adjustment. To this end I may provide a large number of 45 openings 137, each on a radius extending from the axis of the shaft 25 and the radius through each perforation 137 being displaced from the radii through the other openings. The number of openings 137 may, of course, be multiplied to 50 any extent within the available area of the indexing plate but I prefer to utilize thirteen openings in each set, four of the openings in each set being shared in common with adjacent sets, and the openings being arranged in such a way that the radii through all of the openings of a 55 set are separated by a predetermined angle which is sufficiently small to enable the button selector to be assembled with its stop pin 109 in one of the openings of a set, and so assembled 60 to be sufficiently accurately indexed to permit automatic tuning to a desired adjusted position, it being understood that when used in connection with a modern radio receiver that satisfactory tuning may be had even though the receiver is 65 adjusted within a few degrees of the point of maximum accuracy. The perforations 137, however, are arranged so that the angular displacement of their corresponding radii is less than the permissible variation in tuning a radio 70 receiver.

For convenience the openings 137 are also arranged in a plurality of concentric rings about the central opening 135, the pin carrying link 107 being provided with a pair of openings in 75 either of which the pin 109 may be mounted, the

pin, when carried in the inner link opening, being adapted for assembly in a selected perforation 137 of an inner ring of openings. If the pin is mounted in the more remote opening of the link 107 it will be adapted for assembly in 8 one of the perforations of the outer ring of openings.

In order to index the stop pins 109, the escutcheon plate is removed by loosening the holding elements 99, thus revealing the push-button 10 assemblies and permitting each to be removed from the indexing plates. The rotatable adjusting means, including the indexing plates, the spider and the shaft of the device 13, are then rotated manually to bring the same to a desired 15 adjusted position. The pin 109 of a push-button is then inserted through the openings 137 of the plates 89 and 91, which are most closely in alignment with the stop pin 111. The proper openings 137 in which to insert the pin 109 may 20 be determined by visual inspection since the same are those through which the pin 111 may be seen. To facilitate this operation I may color the pin 111 to render the same more highly visible through the openings 137 and the pin is 25 preferably colored black for this purpose, and is displayed against a preferably light background provided by a reflector plate 139, which may be mounted on the bracket 113 in position extending through and anchored in the openings 30 125 behind the pin 111. This reflector plate 139 may comprise a strip of sheet metal preferably coated with white paint or other means forming a background against which the contrasting pin 111 may be displayed. The reflector plate 35 139 also may be thus mounted in position to be illuminated by lamps mounted behind the dial for the purpose of illuminating the same as hereinafter described, these lamps being in position to shine upon reflector plate 139 and in order 40 to provide a background against which the pin 111 may be displayed in highly contrasting fashion.

It will be seen that all of the push-button assemblies may thus be indexed or oriented on 45 the plates 89 and 91 to stop the same at a desired adjusted position of the adjustable means 13. It will also be apparent that the required indexed position of each button assembly may be any one of a plurality of angular positions 50 on the indexing plate means, so that the relative angular position of the exposed face of the button 103 with respect to the escutcheon plate cannot be determined in advance of the button indexing operation. The push buttons may 55 comprise dished elements 141 turnably mounted on the end of the stem 101 which also carries the link 107 extending radially outwardly thereof, the link being preferably fixed on the stem 101. The dished element 141 is normally held 60 against turning by the spring-like washer 143 which is held in place on the stem by means of a washer 145, over which the end of the stem 101 is riveted or peened, as at 147. This construction will normally hold the dished element 141 65 against rotation on the pin 101, but will permit turning if sufficient force is supplied for that purpose. The push-button includes also a cover element 149 which may be assembled upon the dished element 141 in order to close the same. 70 A transparent window element 151 is held upon the dished element 141 by means of the cover 149, which has lugs 153 to hold the same and the window in place on the dished member. The transparent window element may receive 75

an indicia card 155 on which may be marked a designation of the setting controlled by the push-button. The push-button assembly may, of course, be made at the factory, except that 5 the indicia card 155 remains blank. When the button assembly however is indexed, the adjusted position to which the assembly is indexed may be marked on the card by removing the cover 149 and then replacing the same after the card 10 is marked. No care need be taken to properly align the indicia card in the button when the marked card is thus assembled in order to take care of the angulated indexed position of the button assembly since after the indexing is completed, 15 the head of the button may be turned on the stem 101, the spring 143 yielding to permit such turning movement in order to orient the indicia to a desired, readily readable position.

In adjusting radio receiving apparatus for the 20 tuning of the same where the tuning operation involves the rapid movement of the adjustable portions thereof through a plurality of tuned station receiving positions, the receiver may instantaneously emit blurry sounds in passing through 25 the tuned positions in reaching a position to which it is desired to adjust the apparatus. This condition is somewhat undesirable and I propose to eliminate the same by incorporating switching means for rendering the equipment 11 inoperative 30 during automatic tuning by means of the push-buttons and escutcheon plate. To this end I provide switch means operable upon depression of any of the buttons 103 to render the set inactive until the button is released at the compression of the automatic tuning operation. To 35 illustrate this phase of my invention I have shown, on the drawings, a pair of segmental strips 157, which are mounted preferably at an edge of the indexing plate 89 in any suitable fashion, as 40 by means of fastening rivets 159. These plates 157 provide insulated supports for switch contact means 161, which may conveniently be formed, as illustrated in sections 163, arranged in end to end contacting relationship and supported by the insulating strips 157. The sections 45 163 preferably comprise electrically conducting material arranged to provide mounting portions 165 which are secured on the mounting strips 157, as by means of the rivets 167 and contacting portions 169 extending in position opposite the inner 50 end of the center pins 101 of each of the button assemblies. Upon depression of any button the end of its pin 101 will engage upon the corresponding contact portion 169 of the switch means 55 161, and thus complete a control circuit for quieting the receiving apparatus as long as the button is depressed. The particular mode of connecting the quieting circuit in the radio receiver in order to render the same inactive when any of the 60 buttons 103 are depressed, will readily suggest itself to anyone familiar with radio receivers.

I also prefer to provide switch means 171 for the purpose of controlling a part of the receiver in order to facilitate and insure the tuning of 65 the device to the desired station. Modern radio receivers frequently employ means for accomplishing automatic frequency control, commonly designated A. F. C., whereby a radio receiver when tuned to an adjusted position adjacent but 70 not exactly at the position of accurate adjustment for receiving a station, will nevertheless be drawn into tuned condition electrically rather than mechanically by operation of an A. F. C. circuit. The A. F. C. circuit thus operates to 75 widen the range of mechanical adjustment within

which any given broadcast may be received and reproduced by the receiver, and I may utilize the switch means 171 for the purpose of grounding the A. F. C. circuit of the receiver at the instant of tuning in order to restrict the tuning area at 5 the instant the device reaches the adjusted position determined by the stop means 103, whereby thus to exclude interference at the time when the receiver commences operation in the new, tuned position. To this end the main frame or bracket 10 17 is provided with a seat 173 for a pair of yielding switch blades 175 and a pair of insulating elements 177 for insulating one of the blades 175 from the other and from the frame 17 while electrically connecting said other blade on the frame 15 which is grounded. The blades 173 carry switch contacts 179 which are normally held open due to the resilience of the blades. The grounded blade carries a bracket 181 in which is mounted a roller 183 in position to engage a cam element 185 20 which in turn is mounted on the tilting bracket 113. The cam element 185 has a notched edge in position engaging the roller 183. When the bracket 113 is in its neutral position, as shown in Figure 8, the roller 183 will be seated in the bottom of the notch of the cam element in position such that the contacts 179 are out of engagement. The insulated blade 175 may be electrically connected with the A. F. C. circuit of the 25 receiver 11 and, consequently, as the pin 109 engages the stop portion 111 of the bracket 113 the cam element 185 will be rocked in one direction or another to press the roller 183 outwardly, as shown in Figure 7, thus causing closure of the contacts 179 and grounding of the A. F. C. circuit 30 of the receiver. As soon as the button 103 is released, however, at the completion of the tuning operation, the spring portions 175 will resiliently urge the roller 183 against the cam 185 and cause the bracket to return to a neutral position permitting the contacts 179 to open and restore the 35 A. F. C. circuit of the receiver to normal operation. 40

I prefer also to provide means, preferably under the control of a manually turnable knob 187 which 45 is exposed outwardly of the cabinet 87, adjacent an edge of the escutcheon plate 71, for turning the adjustable element 13 to any desired adjusted position, including positions intermediate the adjusted positions accomplished by the push-buttons 50 103. To this end the knob 187 may be connected on a shaft 189 extending through the wall of the cabinet and drivingly connected with a pulley 191 on which travels a flexible belt or cord 193 which travels also in a groove 195 formed in an edge of 55 one of the indexing plates, preferably the plate 89, whereby the rotatable assembly, including the escutcheon plate, the indexing plates, the spider 57 and the shaft 25 of the element 13 may be turned by operating the knob 187 independently 60 of operation by the push-buttons.

I prefer also to provide a geared driving connection between the shaft 189 and the pulley 191, whereby the pulley may be rotated relatively slowly when the shaft is in normal position and 65 may be rotated relatively more rapidly by shifting the shaft 189 axially, as by pulling on the knob into high ratio position.

The dial 35 may be of any preferred construction embodying a scale or scales calibrated to the 70 adjustable device so that the pointers 43 and 45 may indicate the adjusted position of the device 13 at all times on the dial. I prefer, however, to utilize an illuminated dial and have illustrated a novel dial arrangement suitable for use in con- 75

nection with the selective adjusting mechanism heretofore described, although it will be obvious that the novel features of the dial are not necessarily restricted to dials for radio receivers but 5 may be utilized in indicators generally. The illustrated dial construction comprises translucent means 193, preferably a plate of glass, and a sheet of pyrolin or Celluloid. The glass plate may be etched as at 195 to provide a clock scale and a 10 preferably uniformly whitened surface inwardly of the clock scale while the transparent chart may be formed to provide scales in position to be displayed in front of the whitened area of the glass plate. Where the indicator is used in a 15 radio receiver, the scales may comprise a plurality of indicating scales 197, 199, 201 and 203 arranged preferably in the manner described in the co-pending application of Cornelius G. Ely and Earl H. Allen, Serial No. 39,320, filed September 20 5, 1935. The plate 193 is preferably mounted in front of a preferably opaque screen 205, formed with windows 207 arranged in position opposite the central portions of the scales 197, 199, 201 and 203. The plate 193 also may have indicia 25 thereon for identifying the scales, said indicia being arranged opposite the windows 207. The plate 193 also may be secured on the screen 205 by means of holding lugs 209, and to this end I prefer to form the screen 205 as a sheet metal 30 blade having integral lugs 209 formed thereon. The plate 205 is secured as by welding or any other preferred fashion on the mounting bracket 39, which has laterally extending lugs 211 for receiving lamp supporting clips 212 in which lamps 35 214 may be mounted and supported from the frame 39 in position extending behind the openings 207 in position to illuminate the dial plate 193 through said openings and provide an indication by selectively energizing the lamps to show 40 which of the scales of the plate 193 is in condition showing the adjusted position of the device 13. To this end the bracket 39 is or may be formed with partition means 213 adapted to screen each of the dial illuminating lamps from 45 illuminating the dial through any of the openings 207 except that opposite which the lamp is mounted. With this arrangement the dial illuminating lamps will be selectively operated to illuminate only one scale at a time, depending 50 upon the operating condition of the equipment 11 which, of course, may be adjusted for operation under conditions represented by the several scales 197, 199, 201 and 203, by control means 55 215 having a control element 217 projecting outwardly of the cabinet 87 in position for manipulation. Operation of the knob 217 to change the operating condition of the apparatus 11 will also control which of the dial illuminating lamps is energized at any instant or during any operating 60 period. Lamps also may be clipped on the legs of the bracket 39 in position to illuminate the finger pieces 103.

Where it is undesirable or unnecessary to provide for selectively illuminating the scales I may 65 provide a somewhat more simple indicator construction. For example, I may substitute for the frame 39, a substantially dished housing, the bottom of which is secured on the mounting portions 31, the open top facing toward the window 83 and 70 the edges of said housing forming a seat for receiving the edges of the dial means 35. In such an arrangement the edges of the dished housing may be formed with lugs adapted to curl about and interfit with the edges of the dial means to 75 secure the same in place upon the dished element.

In such an arrangement also it is not essential to employ a glass plate such as the plate 193, but all of the scales, including the clock scale, may be formed on a pyrolin or Celluloid sheet to form the indicator. Illumination for the indicator, however, may be provided by lamps mounted within the dished housing element behind the scale carrying sheet.

In connection with radio receiving apparatus generally, and especially in connection with adjustable radio apparatus having the novel selector mechanism herein described, I prefer to mount the adjustable mechanism substantially rigidly on the radio receiver 11, and to this end provide the carrying frame 21 comprising an elongated, preferably sheet metal element bent to provide preferably parallel flanges 217 and an interconnecting wall 219, providing a rigid frame on which the bracket 17, and the support channel 23, may be mounted, the rigid bracket affording means 20 for mounting the adjusting mechanism upon the frame or container of the receiver apparatus 11, to the end that the adjustable device 13 and the adjusting mechanism may be maintained in proper alignment. I prefer also to mount the apparatus 11 and the adjustable means and mechanism carried thereby in a cabinet 221 having curved corner and end wall portions 223. Since I find that this cabinet structure is particularly well suited for housing acoustical devices, and particularly radio receivers, since the same eliminates reverberation and boom due to the non-vibrating characteristics of curved wall portions. The radio receiver apparatus may also include 30 various adjustments such as tone control, volume control, and beacon tuning control accomplished through manually adjustable knobs 225—229 and 231, in addition to the band selection control 217 and the manual adjustment provided by the knob 181. The cabinet 219 also may and preferably 35 does include a loud speaker or sound reproducing mechanism indicated generally at 233.

It is thought that the invention and numerous of its attendant advantages will be understood from the foregoing description and it is obvious that numerous changes may be made in the form, construction, and arrangement of the several parts of the illustrated apparatus without departing from the spirit or scope of my invention or sacrificing any of its attendant advantages, the preferred modes and forms herein described being merely for the purpose of illustrating the invention.

What I claim as new and desire to secure by Letters Patent of the United States is:

1. Selective adjusting mechanism comprising a manually shiftable element and selectively operable means for stopping movement of said element when a desired adjusted position of said element is reached comprising a plurality of stems depressible on said element, a stop pin on each stem and depressible therewith into stopping position, means normally urging each stem and its associated pin toward non-stopping position, said element having a plurality of openings for the stop pin of each stem, said openings being laterally offset with respect to each other whereby each of said pins may be indexed in any one of a plurality of relatively offset positions, each of said pins being secured to its associated stem by means of a link extending radially of said stem, at least some of said links providing for mounting the pin parallel with the stem at various distances therefrom and wherein said shiftable element has a perforation for the recep- 75

tion of each stem and a plurality of perforations disposed about each stem perforation in concentric circular arrangement so that by mounting the pin in various positions on the link, it 5 may be indexed in any one of said concentrically arranged openings.

2. Selective adjusting mechanism comprising a manually shiftable element and selectively operable means for stopping movement of said 10 element when a desired adjusted position of said element is reached comprising a plurality of stems depressible on said element, a stop pin on each stem and depressible therewith into stopping position, means normally urging each stem 15 and its associated pin toward non-stopping position, said element having a plurality of openings for the stop pin of each stem, said openings being laterally offset with respect to each other whereby each of said pins may be indexed in any 20 one of a plurality of relatively offset positions, each of said stems being provided with a button forming a housing for indicia means for indicating the adjusted position controlled by the button, said button being yieldingly held against relative 25 rotation on said stem but being turnable thereon to orient said indicia after the stem and its stop pin have been indexed and assembled on the shiftable element.

3. Selective adjusting mechanism comprising 30 a manually shiftable element and selectively operable means for stopping movement of said element when a desired adjusted position of said element is reached comprising a plurality of stems depressible on said element, a stop pin on 35 each stem and depressible therewith into stopping position, means normally urging each stem and its associated pin toward non-stopping position, said element having a plurality of openings for the stop pin of each stem, said openings being laterally offset with respect to each other whereby each of said pins may be indexed in any one 40 of a plurality of relatively offset positions, said manually shiftable element comprising a frame embodying a pair of plates of similar construction 45 having aligned openings for the stems and associated stop pins, said plates being secured in spaced relationship and at least one of them having a groove, auxiliary adjusting means for turning the shiftable element to any adjusted 50 position thereof independently of the stop means comprising said pins, said auxiliary adjusting means comprising a manually turnable pulley and a belt transmission travelling said pulley and the groove of said plate, said auxiliary adjusting 55 means having a plurality of operating positions, in one of which the pulley is turned relatively more rapidly than another in response to manipulation of said auxiliary adjusting means.

4. Selective adjusting mechanism comprising 60 a manually shiftable element and selectively operable means for stopping movement of said element when a desired adjusted position of said element is reached comprising a plurality of stems depressible on said element, a stop pin on 65 each stem and depressible therewith into stopping position, means normally urging each stem and its associated pin toward non-stopping position, said element having a plurality of openings for the stop pin of each stem, said openings 70 being laterally offset with respect to each other

whereby each of said pins may be indexed in any one of a plurality of relatively offset positions, and sighting means mounted in position behind the pin receiving perforation portion of the shiftable element to indicate in which of said openings the stop pin should be assembled for indexing purposes. 5

5. Selective adjusting mechanism comprising a manually shiftable element and selectively operable means for stopping movement of said element when a desired adjusted position of said element is reached comprising a plurality of stems depressible on said element, a stop pin on each stem and depressible therewith into stopping position, means normally urging each stem 15 and its associated pin toward non-stopping position, said element having a plurality of openings for the stop pin of each stem, said openings being laterally offset with respect to each other whereby each of said pins may be indexed in any 20 one of a plurality of relatively offset positions, and a sighting bar mounted in position behind the perforated portion of said shiftable element to indicate in which of said openings the stop pin should be assembled for indexing the same, and 25 means behind said sighting bar for increasing its visibility through said perforation.

6. Selective adjusting mechanism comprising a manually shiftable element and selectively operable means for stopping movement of said element when a desired adjusted position of said element is reached comprising a plurality of stems depressible on said element, a stop pin on each stem and depressible therewith into stopping position, means normally urging each stem 30 and its associated pin toward non-stopping position, said element having a plurality of openings for the stop pin of each stem, said openings being laterally offset with respect to each other whereby each of said pins may be indexed in any one 35 of a plurality of relatively offset positions, a sighting bar mounted in position behind the perforated portion of said shiftable element to indicate in which of said openings the stop pin should be assembled for indexing the same, and 40 illuminated means behind said bar for increasing its visibility through said perforation. 45

7. Selective adjusting mechanism comprising a manually shiftable element and selective means operable during and as a part of the shifting of 50 said element to stop the same when a desired adjusted position is reached, said selective means comprising a plurality of selectors individual and selectively depressible on said manually shiftable element, each depressible selector comprising a 55 guide stem and a cooperating stem-like stop element axially movable on the manually shiftable element, means normally urging said guide stem and stop element toward inactive position on the shiftable element, means forming a cooperating 60 stop adapted to engage said stop element when the selector is depressed on said shiftable element whereby to stop the shiftable element in a position determined by said stop element, said stop element having a stem-like portion adapted 65 to extend substantially parallel with respect to the guide stem, and means to adjust the distance between said stop element and its associated guide stem.
